UNITED STATES PATENT OFFICE.

HERBERT E. VAN DORN, OF CHICAGO, ILLINOIS.

DRAW-BAR CARRIER.

1,251,943.

Specification of Letters Patent.

Patented Jan. 1, 1918.

Application filed November 26, 1915. Serial No. 63,630.

To all whom it may concern:

Be it known that I, HERBERT E. VAN DORN, a citizen of the United States, and a resident of the city of Chicago, in the county of Cook and State of Illinois, have invented certain new and useful Improvements in Draw-Bar Carriers; and I do hereby declare that the following is a full, clear, and exact description of the same, reference being had to the accompanying drawings, and to the numerals of reference marked thereon, which form a part of this specification.

This invention relates to an improved type of carrier or support for the drawbar on a car, and in the particular construction illustrated one wherein the drawbar is connected at one end to a draft gear and at its other end has attached thereon a coupler head which is held properly supported by the drawbar.

It is an object therefore of this invention to construct a device adapted for sliding connection with a guide beneath the car and with the end of a drawbar to permit movement of the drawbar about its pivot and also to permit a longitudinal movement of the drawbar consequent upon variations in the position of its pivot due to movement of the parts of the draft gear to which the drawbar is connected.

It is also an object of this invention to provide a construction wherein a drawbar is so constructed as to coöperate with a supporting member which has slidable movement beneath a car to permit swinging movement of the drawbar about its pivot, as well as longitudinal movement thereof due to variations in position of the elements of the draft gear to which the drawbar is connected.

It is furthermore an important object of this invention to provide in combination with a longitudinally movable and pivoted drawbar means for supporting the same in any position of adjustment thereof.

It is finally an object of this invention to construct a device for supporting the drawbar in all positions of adjustment, permitting easy movement of said drawbar into any position and provided with wear plates to obviate to a great extent appreciable wear on the construction.

The invention (in a preferred form) is illustrated in the drawings and hereinafter more fully described.

In the drawings:

Figure 1 is a fragmentary top plan view illustrating a drawbar supporting a coupler head and connected to a draft gear and associated with supporting and guiding means detached from a car.

Fig. 2 is a fragmentary side elevation with a portion of the car shown in section illustrating the drawbar and supporting device therefor in position on the car.

Fig. 3 is a detail section taken on line 3—3 of Fig. 1, with parts omitted.

Fig. 4 is a detail section taken on line 4—4 of Fig. 3, with parts omitted.

Fig. 5 is a top plan view of the slidable carrier element detached from the drawbar and from the guide track.

Fig. 6 is a detail section taken on line 6—6 of Fig. 5.

Fig. 7 is an end view of the slidable carrier element.

As shown in the drawings:

The reference numeral 1, indicates as a whole the end frame of a car of any suitable type, having a platform extension 2, and secured beneath the end of the frame 1, of the car, is any conventional type of draft gear 3. Mounted within said draft gear and forming a part thereof and movable against the resisting mechanisms on the interior thereof is a yoke member 4, in which is pivoted a drawbar 5, by means of a pintle or bolt 6. At the other end of said drawbar 5, a yoke 7, is formed, in which is pivoted a coupled head 8, by means of a horizontal pin bolt 9. Mounted beneath the platform extension 2, of the car, is a flat curved guide bar 9^a, the curvature thereof substantially equal to that of a radius struck from the normal position of the pin bolt 6, of the drawbar. Slidably mounted upon said guide bar 9^a, is a carrier block 10, provided in its upper portion with a curved groove or channel 11, curved to correspond with the curvature of said guide bar 9, and in the lower portion of said block 10, a straight downwardly directed T-shaped groove or channel 12, is formed, the axis of which is at right angles to the central radius of curvature of said upper groove or channel 11.

Formed on the upper portion of the drawbar 5, near the outer end thereof, is a T-shaped portion 13, adapted to engage in the T-shaped channel 12, of said carrier block to slide therethrough when longitudinal

movement is imparted to said drawbar 5, by variation in position of the elements in the draft gear 3. As clearly shown in Fig. 6, said carrier block 10, is provided with 5 hardened steel inserts or wear plates 14, on the inner top walls of the groove or channel 11, which bear upon the top surface of the guide bar 9^a, and similarly with wear plates 15, on the lower walls of the groove or channel 12, on which the T-shaped portion 13, of the drawbar rests. Said wear plates are placed within the mold for the block 10, and held in position by pins or integral extensions 10^a, before the block 10, is cast, and 15 then the metal is poured into the mold and forms around said wear plates. Wear plates 13^a, are also provided, recessed into the T-member 13, which bear upon the wear plates 15. Pivoted in a lower extension at the end 20 of the drawbar 5, on a pintle bolt 16, is a lever 17, one end of which bears upwardly beneath the coupler head 8, to hold the same upwardly, and the other end of which is held thrust downwardly to support said 25 coupler head by a compression spring 18, coiled about a bolt 19, disposed vertically in a cored out portion in the end of said drawbar 5, and extending slidably through a slot in the end of said lever 17.

30 The operation is as follows:

The drawbar 5, mounted upon the pintle bolt 6, is capable of swinging in an arc horizontally about the pivot point afforded by said bolt and is capable of a certain amount 35 of longitudinal movement dependent upon conditions imposed thereon due to draft and buffing stresses, causing movement of the yoke 4, in which the pintle bolt is mounted, with respect to the draft gear 3. The 40 slideable carrier block 10, permits movement of the drawbar both longitudinally and pivotally and when swinging about its pivot, the slideable block 10, is moved with the drawbar around on said curved track member 9^a, 45 whereas when longitudinal movement takes place the T-portion 13, of the drawbar slides in the channel 12, of the carrier block.

I am aware that various details of construction may be varied through a wide 50 range without departing from the principles of this invention, and I therefore do not purpose limiting the patent granted otherwise than necessitated by the prior art.

I claim as my invention:

55 1. In a device of the class described the combination with a car and its draft gear and drawbar mounted thereon, of a curved track member secured to the car, a block channeled for engagement therewith to slide 60 thereon, and a T-shaped portion formed on

said drawbar slidably engaging through another channeled portion of said block whereby said drawbar is supported from said track in all positions of adjustment of the drawbar.

2. In a device of the class described the combination with a car and its draft gear and drawbar pivotally mounted thereon, of a curved track member secured to the car, a block channeled for engagement therewith to slide thereon, a T-shaped portion formed on said drawbar slidably engaging through another channeled portion in said block, said block recessed in said respective channeled portions, wear plates seated in said recesses to bear upon the curved track and upon the T-shaped portion of said drawbar respectively, and means retaining said wear plates associated with said block.

3. The combination with a car and its drawbar, of a guide member secured to the car, a block slideable thereon, means affording a slideable connection between said block and drawbar, and a plurality of wear plates recessed into said block for contact with 85 the guide member and said means.

4. In a device of the class described, the combination with a car and drawbar thereof, of a guide member secured to the car, a block slideable thereon having a channel in 90 the underside thereof, wear plates recessed into said block to bear upon said guide member, wear plates disposed in recesses in the walls of the channel of said block, means formed on the drawbar engaging in the 95 channel of said block, and wear plates mounted on said means adapted to contact and bear upon the wear plates in the channel of said block.

5. In a device of the class described, the 100 combination with a car and its draft gear and drawbar, of a track member secured to the car, a block channeled for engagement with said track member and slideable thereon, a T-shaped portion formed on said drawbar 105 slidably engaging through another channeled portion of said block, and wear plates mounted both on said T-shaped portion and within the channeled portion of said block contacting one another to receive the weight 110 of said drawbar supported from said track member in all positions of adjustment of the drawbar.

In testimony whereof I have hereunto subscribed my name in the presence of two 115 subscribing witnesses.

HERBERT E. VAN DORN.
